UNITED STATES PATENT OFFICE.

ARTHUR C. CANDLAND, OF PROVO, UTAH.

RAIL-FASTENER.

1,066,886.

Specification of Letters Patent.

Patented July 8, 1913.

Application filed April 11, 1913. Serial No. 760,561.

To all whom it may concern:

Be it known that I, ARTHUR C. CANDLAND, a citizen of the United States, residing at Provo city, in the county of Utah and 5 State of Utah, have invented certain new and useful Improvements in Rail-Fasteners, of which the following is a specification.

My invention relates to rail fastening devices, and has for its object to provide means 10 for fastening railway rails securely on a metallic channel tie, and to provide a fastener which consists of but few parts and one that is easily placed in position and is adjustable to grip rails having different 15 width base flanges. These and other objects which are apparent I accomplish with the device illustrated in the accompanying drawings, in which similar letters of reference indicate like parts throughout the several figures and as described in the specifications forming a part of this application, and as pointed out in the appended claims.

Figure 1 is a plan view of one end portion of a piece of sheet metal cut, but before it 25 is bent into shape, to form a tie. Fig. 2 is the same after it is bent into shape. Fig. 3 is a longitudinal vertical section through one end of a tie and a portion of a rail secured thereon with my fastener, on line $z-z$ of Fig. 4. Fig. 4 is a transverse vertical section through an end portion of a tie, on line $x-x$ of Fig. 3. Fig. 5 is a view in perspective of one of the rail chairs. Fig. 6 is a view in perspective of one of the rail clamps. Fig. 7 30 is a view in perspective of one of the liners. Fig. 8 is a side elevation of one of the bolts and nut therefor. Fig. 9 is a view in perspective of one of the cushion blocks. Fig. 10 is a modified form of rail chairs.

40 I have observed since filing my application for rail fasteners on September 3rd, 1912, Serial Number 718,401, that, in the construction and use of metallic ties of the channel shape, and the fastening of the rails thereon, the cost of manufacturing and laying a railway track may be materially lessened by cutting down the sides of the tie, and the fastening means made more positive by locking the rail engaging parts 45 against lateral as well as longitudinal movement on the tie. My ties are made of sheet metal which is cut into the form shown in Fig. 1, and then bent into the form shown in Fig. 2, having the sides 1, not over four 50 inches in height, and provided with longitudinal slots 2 therein. On ties of this

shape I place my fasteners, which consist of U-shaped rail chairs 6 and other co-acting elements. Each of said rail chairs has its end portions bent outward and upward to 55 form hook members 7. Said rail chairs 6 are placed in position by springing the sides 1 of the tie out, or by springing the end portions of the said rail chairs toward each other until said hook members 7 may be inserted within said slots 2. Cushion blocks 3, 60 having inclined sides and vertical ends are fitted below said chairs and within said tie. Each of said blocks has an open channel 4 cut in the upper side thereof and grooves 5 65 parallel therewith in the upper edges and longitudinal with said tie. Said blocks are made of wood, fibrous material or concrete having an asphaltum binder, and are placed adjacent said slots 2. In order to accommodate my fastener to rails having different 70 width bases, I bend the edge of each rail chair up as a flange 8, and to use a rail having a narrow base I place a liner 9 between each of said flanges 8 and the base flange of 75 the rail adjacent. Rail clamps 10, each having an elongated circular hole 11 therein, are then placed adjacent said blocks 3 on the inclined sides. If the liners 9 are used, the rail clamps 10 adjacent are inserted from 80 above within the hook shaped ends 20 of said liners and said hooks 20 will hold the said clamps in contact with said block 3. Each of said rail clamps has the upper portion 12 bent at an angle to engage the base 85 flange of a rail that is supported by said rail chair and block. Insulating material 13 may be used around said base flange to insulate said rail from said rail chair and clamps. A threaded bolt 14 having a cone 90 shaped head 15 on one end thereof is inserted through one of said clamps 10 in the elongated hole 11, beneath the rail chair 6, with the other end protruding through the said 95 elongated hole 11 in the other clamp 10. A cone shaped nut 16 when screwed on said bolt will engage the lower end of the said elongated hole 11 and the bottom of said rail chair on one side of the said rail chair, while the cone shaped head 15 of the bolt will likewise engage the opposed clamp 10 and the opposite side of said rail chair and draw 100 said clamps inward and downward in gripping contact with the base flange of the rail. Said rail chairs 6 are prevented from upward movement by said hook members 7 engaging the sides 1 of the tie above the said 105

slots 2. In order that said clamps may grip said rail they must have a movement inward and downward, relative to said rail chairs and for that reason the lower ends of said 5 clamps do not extend to the bottom of the tie, nor does said nut 16 or bolt head 15 engage the upper portion of said elongated holes 11 in said clamps 10. When said cushion blocks 3 are in place within the tie and below 10 the rail chairs they lock the said rail chairs in place and prevent any springing of the sides of the tie or the end portion of the rail chairs. A modified form of the rail chairs is shown in Fig. 10 wherein the end 15 portions of the rail chair are bent inward and upward forming a flanged hook 17 on each end. Said hooks 17 are to be inserted and used within said slots 2 to hold the said chairs 18 in place within the tie. Said 20 chairs 18 are used similarly to said chairs 6.

Having thus described my invention I desire to secure by Letters Patent and claim:

1. In combination with a metal tie of channel shape, having longitudinally disposed slots in the sides thereof; of cushion blocks in said tie having inclined sides; a U-shaped rail chair on each of said blocks having its end portions bent outward and upward to be inserted within said slots and 25 to engage the side of said tie; rail clamps, each having an elongated circular hole therein, placed adjacent said inclined sides of said blocks; a threaded bolt having a cone shaped head inserted through the said 30 elongated holes in said clamps and below said rail plate; and a nut screwed on said bolt having a portion thereof conical in shape.

2. In combination with a channel shaped metal tie, having longitudinally disposed slots in the sides thereof; cushion blocks having two sides of each inclined and channels cut in the upper side adjacent said slots; U-shaped rail chairs, having the ends thereof bent outward and upward to engage within said slots; an upturned flange on one edge of each of said rail chairs; liners adjacent said flanges; clamps adjacent the inclined sides of said blocks and each provided 45 with an elongated circular hole and a portion bent to grip the base flange of a rail; a threaded bolt, having a cone shaped head, inserted through said holes and below said rail chairs, and a cone shaped nut screwed 50 on said bolt tending to draw said clamps in-

ward and downward in gripping contact with the base flange of a rail and to hold said liner in place.

3. In combination with the sides of a channel shaped metal tie, having longitudinal slots therein; cushion blocks having the sides of each inclined outwardly and channels cut in the upper side; a rail chair superimposed on each of said blocks and having each end portion bent to engage in the slots in said tie; an upwardly extended flange integral with one edge of each rail chair; clamps adjacent the inclined sides of said blocks each having an elongated circular hole therein and a portion bent to grip the base flange of a rail; and a threaded bolt and nut screwed thereon adapted when placed in said holes and below said rail chair and tightened to cause said clamp to grip the base flange of a rail. 75

4. In combination with the sides of a channel shaped metal tie having slots therein; of cushion blocks between said slots, having the sides of each outwardly inclined and each provided with open channels in the upper side thereof; a rail chair superimposed on each of said cushion blocks and having the end portions bent downward and outward to engage a portion of the said tie above said slots; an upwardly extended flange on each; liners placed on the said rail chairs contiguous said flanges; clamps contiguous the inclined sides of said blocks and having elongated circular holes therein; a portion of each clamp bent to grip the base flange of a railway rail resting on said rail chairs; insulating sheets between said rail chair and clamps and the base flange of a rail; a threaded bolt having a cone-shaped head inserted through said elongated circular holes and below said rail chair; and a cone shaped nut adapted when screwed on said bolt to contact with the lower end of one of said elongated circular holes and with the under side of said rail chair and to draw said clamps downward and inward in gripping contact with the base flange of the rail resting on said rail plate and to prevent said liners from vertical displacement. 95

In testimony whereof I have affixed my signature in presence of two witnesses.

ARTHUR C. CANDLAND.
